UNITED STATES PATENT OFFICE.

JAHN K. MARTINKA AND ELIZI K. MARTINKA, OF NEW YORK, N. Y., ASSIGNEES OF
ONE-THIRD TO MARTIN TOMECEK, OF NEW YORK, N. Y.

EGG-TESTER.

1,400,966.

Specification of Letters Patent. Patented Dec. 20, 1921.

Application filed December 6, 1920. Serial No. 428,543.

To all whom it may concern:

Be it known that we, JAHN K. MARTINKA, and ELIZI K. MARTINKA, citizens of Czechoslovakia, residing at New York, in the county of New York and State of New York, have invented certain new and useful Improvements in Egg-Testers, of which the following is a specification.

This invention relates to certain new and useful improvements in egg testers of that type embodying a receptacle having an open top interiorly shaped to snugly engage a portion of an egg so as to provide a seat for the latter, and a mirror in the receptacle beneath the open top for reflecting such light as passes through the egg, the light being observable through a side opening provided in the side of the receptacle at a convenient point above the mirror.

20 The primary object of the invention is to provide an egg tester of this kind which is extremely simple and durable in construction as well as capable of being placed into efficient and practical use by a relatively unskilled person, which is made more readily possible by the provision of means for adjusting the mirror toward or away from the egg and side opening so as to obtain proper reflection.

30 With the above and other objects in view, the present invention consists in the novel form, combination and arrangement of parts hereinafter more fully described and shown in the accompanying drawings, 35 in which like reference characters designate corresponding parts throughout the several views.

In the drawing,

Figure 1 is a view partly in elevation and 40 partly in vertical section of an egg tester constructed in accordance with the present invention.

Fig. 2 is a horizontal sectional view thereof taken substantially upon line II-II 45 of Fig. 1 and

Fig. 3 is an elevational view of the same with parts broken away.

Referring more in detail to the several views, the present invention embodies a 50 receptacle including an upright tubular body 5 having open ends and with the interior of its upper end shaped as at 6 to conform to a portion of an egg 7 so as to provide a seat for the latter whereby it is 55 supported in position as shown in Figs. 1

and 2, partially within the open upper end of said body. The body 5 is provided with a removable bottom 8 which may be detachably held in place or secured to the body 5 by any suitable means such as the pin and bayonet slot connections 9 upon opposite sides thereof. Suitable resilient supporting legs 10 are rigidly fastened in any suitable manner to the bottom member 8 whereby the receptacle is supported 60 in spaced relation to a table or the like on which the device is placed.

An adjusting screw 11 is positioned centrally of the bottom member 8 and in threaded engagement therewith so as to extend axially within the body 5, and a supporting member 12 slightly smaller in diameter than the internal diameter of the body 5 is supported upon the upper end of the screw 11 and carries a mirror 13 as shown 75 in Fig. 2 arranged directly beneath the egg 7. The lower end of the screw 11, exteriorly of the receptacle, is provided with a wing handle 14 for permitting the screw 11 to be readily turned so as to adjust the 80 mirror 13 to any desired extent longitudinally of the receptacle whereby it is brought closer to or farther away from the egg 7 so as to insure most practical results by properly reflecting the light for being 85 viewed through the side opening 15 provided in the body 5, under varying light conditions. Handles 16 are carried by the opposite sides of the body 5 to facilitate the moving of the tester. 90

In operation, the egg is placed upon the seat 6 as shown in Figs. 1 and 2 and external light passes through the egg and the open upper end of the body 5 to the reflector 13 where it can be viewed through the opening 15. The relative freshness of the egg 95 can be thus readily ascertained by noting the brightness of the light in the reflector, it being a well known fact that a fresh egg will permit the passage of light there- 100 through more freely than an egg which is not so fresh or which is not good.

From the foregoing description, it is believed that the construction and operation of the present invention will be readily understood and appreciated by those skilled in the art.

Minor changes may be made without departing from the spirit and scope of the invention as claimed.

What is claimed as new is:

An egg tester including an upright receptacle having a tubular body portion provided with an open upper end formed inferiorly to conform to a portion of an egg for providing a supporting seat therefor and provided with a sight opening in the side thereof immediately below the open upper end, a detachable bottom plate, carrying supporting legs, for the said tubular

body, a removable reflector within the body portion and vertically adjustable therein, and a single supporting bar centrally attached to said reflector and screw-threadedly mounted within the central portion of the removable body plate.

In testimony whereof we affix our signatures.

JAHN K. MARTINKA.
ELIZI K. MARTINKA.
